CERTIFICATE OF CORRECTION

PATENT NO. : Des. 453,749 S
DATED : February 19, 2002
INVENTOR(S) : Jae Kyung et al.

Page 1 of 7

It is certified that error appears in the above-identified patent and that said Letters Patent is hereby corrected as shown below:

The title page, showing the illustrative figure, should be deleted and replace with the attached title page.

Please substitute the drawings that appear on the patent with the attached figure 1-8.

Signed and Sealed this

Eleventh Day of February, 2003

JAMES E. ROGAN
Director of the United States Patent and Trademark Office
